UNITED STATES PATENT OFFICE

130,264

DESIGN FOR A PASTRY BRUSH

Albert Racicot, Aurora, Ill., assignor to National Brush Company, Aurora, Ill., a corporation of Illinois

Application June 21, 1941, Serial No. 101,606

Term of patent 7 years

To all whom it may concern:

Be it known that I, Albert Racicot, a citizen of the United States, residing at Aurora, in the county of Kane and State of Illinois, have invented a new, original, and ornamental Design for a Pastry Brush, of which the following is a specification, reference being had to the accompanying drawing, forming part thereof, in which:

Fig. 1 is a face elevational view of the pastry brush showing my new design;

Fig. 2 is a side elevational view thereof; and
Fig. 3 is an end elevational view thereof.

I claim:

The ornamental design for a pastry brush,
substantially as shown.

ALBERT RACICOT.
